UNITED STATES PATENT OFFICE

104,295

DESIGN FOR A TEXTILE FABRIC

William Rosenberg, New York, N. Y.

Application April 2, 1937, Serial No. 68,527

Term of patent 3½ years

To all whom it may concern:

Be it known that I, William Rosenberg, a citizen of the United States of America, residing in city of New York, county of New York, and State of New York, have invented a new, original, and ornamental Design for a Textile Fabric, of which the following is a specification, reference being had to the accompanying drawing, forming part thereof,

The figure is a plan view of a textile fabric showing my new design. The dot and dash lines on the drawing show the design unit, which unit is repeated in staggered succession, as indicated by the angles A and A'.

I claim:

The ornamental design for a textile fabric, substantially as shown and described.

WILLIAM ROSENBERG.
